UNITED STATES PATENT OFFICE.

EDWARD H. JOHNSON, OF NEW YORK, N. Y.

TELEPHONE.

SPECIFICATION forming part of Letters Patent No. 443,526, dated December 30, 1890.

Application filed April 24, 1884. Serial No. 129,065. (No model.)

To all whom it may concern:

Be it known that I, EDWARD H. JOHNSON, of New York city, in the county and State of New York, have invented a certain new and useful Improvement in Telephone-Transmitters, of which the following is a specification.

The object I have in view is to produce a telephone-transmitter for transmitting articulate speech, capable of use directly in the line, which may be kept constantly charged by a battery located at either end of the line or at the exchange or central office, and proportioned to the length of the line. In this way a telephone-exchange system could be produced wherein no batteries would be required at the subscribers' telephones and no induction-coils would be necessary, the transmitters acting directly upon a line-current of constant direction to vary it by throwing it into pulsations practically in unison with the sound-waves. The receivers would also be directly in the line, and since the line would be constantly charged simple electro-magnetic receivers could be employed, the diaphragms being kept under tension by the constant current, and no permanent magnets being required for that purpose. The instrument is designed to produce great variations in the line-current, similar to those produced by a telegraph-key, and hence by properly proportioning the transmitter and receiver to the resistance of the line the same length of line may be used as in telegraph systems, and the telephone system will be reduced to the simplicity of arrangement employed in the present Morse telegraph. The deleterious effects of induction from adjoining lines will also be overcome.

While my transmitter has advantages of being adapted for the use explained, it is also capable of use with induction-coils, like the carbon transmitter, when proportioned or connected properly for such purpose.

The invention covered by the present application for patent is limited to the telephone-transmitter *per se*, however it may be used.

In carrying out my invention I make use of a number of independent and free circuit-controllers acted upon independently by the sound-waves and free to move in unison with the condensations and rarefactions of the

atmosphere produced by the vocal organs. These circuit-controllers serve to vary the number of definite units of current in the telephone-circuit by changing the number of definite units of resistance or counter electro-motive force in circuit, or both.

For my instrument I employ for each circuit-controller the arrangement shown and described in my patent, No. 381,382, dated April 17, 1888, or any modification thereof covered by such application, and mount a number of these circuit-controllers in one instrument, with the heads of the piston sound-wave receivers in a common sound-wave-receiving chamber. The magnet or solenoid coils are connected in any desired arrangement of series, multiple series, or multiple arc in one circuit, which may be the line-circuit or the primary of an induction-coil. I arrange all the independent circuit-controllers so that they are all situated at different distances from the central point. I prefer an arrangement in the form of a geometrical spiral. I find that this arrangement of the circuit-controllers, so that they are all at different distances from the central point, gives the best results in the transmission of speech, and I believe this to be due to the fact that there is a progressive action of the different circuit-controllers.

In the accompanying drawings, forming a part hereof, Figure 1 is a front view of the instrument, the door of the inclosing-box being thrown open; Fig. 2, a side elevation of the instrument with the inclosing-box in section; Fig. 3, a view from the rear of the instrument; Fig. 4, a sectional view, on an enlarged scale, of one piston sound-wave receiver and the parts connected therewith; Fig. 5, a vertical section of four of the piston sound-wave receivers arranged in two series, and Fig. 6 a representation of the current-pulsations caused by the instrument when used directly in line.

In the block A, of hard rubber or other suitable insulation, are mounted a number of the independent circuit-controllers having the arrangement of a geometrical spiral, as shown in Figs. 1 and 2. Each is composed of an electro-magnet B, a piston sound-wave receiver C, carrying armature *a* and guided and retarded in its movement, and points *b*, *c*,

of platinum or other suitable metal, carried by the magnet and armature, as shown, these parts being more particularly described in my patent, No. 381,382, dated April 17, 1888.

- 5 Each magnet B is carried by the hollow end of a plug D, of hard rubber or other suitable insulator, having an enlarged head which fits tightly one of the openings through the block A and is forced therein. The body of 10 the plug does not quite fill the opening in block A, and in the annular space thus formed the piston C works freely, being guided both internally and externally by the plug D and the block A. The heads of all the pistons are 15 flush with the face of block A. This block is inclosed in a suitable case E, having door F and mouth-piece G, and this case forms a common sound-receiving chamber for all the pistons. The wire of each magnet is soldered 20 at one end to the magnet-core, and the other end is carried out through the plug D to the back of block A. A connection 2 is made with the core of each magnet, and is carried out through plug D to the back of block A. 25 A pin d extends through the block A adjacent to each circuit-controller, and on the front of the block is connected by a wire 3 with the armature a and electrode c, while on the back of the block it is connected with magnet-wire. 30 1. It will thus be seen that in each circuit-controller the coils of the magnet and the electrodes b c bear a shunt relation to each other, the contact of the electrodes short-circuiting the magnet-coils and the separation 35 of the electrodes throwing such coils into circuit. All the circuit-controllers are connected in one circuit 4 5. This connection may be any desired arrangement of series or arc.

In Fig. 5 by utilizing the end connections 40 6 7 only the circuit - controllers would be placed in one series, while by the use of connection 8 two series can be formed. Six binding - posts e' e² e³ e⁴ e⁵ e⁶ are shown, to which run connections 9 10 11 12 13 14, dividing 45 the circuit-controllers into five series. By their use a simple series or a number of arrangements in multiple series can be made. I prefer for an instrument to be used directly in the line to employ a simple series arrangement; but with an induction-coil a multiple 50 series or multiple-arc arrangement would be preferable, although the particular arrangement in either case would depend upon the resistance of the line and the resistance and 55 power of the magnets.

The magnet-coils form the definite units of resistance, which are thrown into and out of circuit by the circuit-controllers. This resistance, however, is multiplied by the coun-

ter-electro-motive force of the magnet when 60 the short circuit is broken, and a much greater reduction of the current is produced than would be due to the introduction of the resistance of the wire alone, and the pulsations are sharpened by the partial or complete 65 neutralization of the static charge.

I propose using a much larger number of circuit - controllers in my instrument than shown in the drawings, although a lesser number could be employed, and for long lines 70 these are preferably arranged in series.

By the operation of the line-transmitter the current is thrown into pulsations which are in unison with the articulate sound-waves.

The pulsatory current is illustrated diagrammatically in Fig. 6. The line e represents no current. The line f represents the current when all the resistance is in circuit. The line g represents the current when the resistance is all cut out of circuit. The telephone - circuit being constantly charged by a current of one direction, at no time will there be less current flowing than represented by line f. The pulsations caused by the transmitter are represented by the zigzag 85 line h, varying between the lines f g, since the pulsations will vary between points of maximum and minimum current.

What I claim is—

1. In a telephone-transmitter, the combination, with one circuit, of two or more sets of electrodes and definite units of resistance located in shunt-circuits around such electrodes, substantially as set forth.

2. In a telephone-transmitter, the combination of two or more sets of electrodes, two or more piston sound-wave receivers, and electrically - operated devices for automatically adjusting the electrodes and forming definite units of resistance which are thrown into and 95 out of circuit by the movement of the electrodes, substantially as set forth.

3. In a telephone-transmitter, the combination of a number of sets of electrodes and independent controlling devices arranged at different distances from a central point, substantially as set forth.

4. In a telephone-transmitter, the combination of a number of sets of electrodes and independent controlling devices spirally arranged, substantially as set forth.

This specification signed and witnessed this 9th day of April, 1884.

EDWARD H. JOHNSON.
